UNITED STATES PATENT OFFICE.

LEON MANNING, OF CUBA, NEW YORK.

WINDOW-SASH FRAME AND OTHER FRAME.

Application filed February 19, 1926. Serial No. 89,412.

This invention relates to window sash frames or other frames which are movable to a convenient position to enable both sides thereof to be washed without the necessity 5 of a person assuming a dangerous and precarious position.

Objects of this invention are to provide a window sash having new and improved features of construction and arrangement 10 which enables access to both sides of the window to be readily and conveniently had from the inside of a room; to enable the window to be sealed in an efficient manner so that but two parts of the inner frame are 15actable with the outer frame, thereby providing a "two point contact"; to provide a practical drain in the base of the frame so that water may flow to the outside of the sash; to overcome sweating or steaming of 20 the inside of the window; and to provide a sash having the novel features of construction and arrangement hereinafter described.

The invention is shown by way of illustration in the accompanying drawings, in 25 which:

Fig. 1 is an elevation of the sash from the inside thereof; Fig. 2 is an enlarged sectional view on the line 2—2 of Fig. 1; Fig. 3 is a transverse sectional view of the inner 30 and outer frame showing the inner frame swung outwardly; Fig. 4 is a fragmentary elevation of the outer frame showing the pivotal mounting for the inner frame; and Fig. 5 is a fragmentary elevation of a portion 35 of the inner frame.

The illustrated embodiment of the invention comprises a sash having an outer frame 1 and an inner frame 2, both preferably being of shell type construction. The sash is 40 adapted for sliding engagement in a window frame guide of the usual type and is intended to replace or be substituted for windows which are at present in use in a simple manner without the necessity of special construction.

The outer frame 1 consists of horizontal bars 3 and 4 and vertical bars 5 and 6, which 50 provide an opening 7 within which the inner frame 2 is disposed. The particular construction of the outer frame is clearly shown in Fig. 2, and attention is directed to the

flange 8 at the front portion thereof which is inclined inwardly and which defines the opening 7 in the outer frame. The flange 8 extends entirely around the opening, and is 55 engageable with the outer or front side of the inner frame, as will hereinafter appear.

Spaced from the base of, but forming a part of the outer frame 1, is a plate 8^a which extends transversely across such frame. Formed in the upper surface of the plate 8^a 60 are longitudinal grooves or ducts 9. Terminating at the central portion of this plate is an outturned portion 10 which registers with a port 11 in the outer side of the frame 1. The ducts 9 form a drain and are inclined 65 downwardly to the port 11, so that water may be readily drained from the inside of the sash. This has been found to be exceedingly useful in washing the window, and in the event rain enters the inside of the sash.

The inner frame 2 is provided with upper and lower laterally extending brackets 12 and 13 at one side thereof. Each bracket is provided with an elongate opening 14 through which extends a post 15 which is 70 mounted in the outer frame 1.

The lower portion of the post 15 fits into a socket member 16 on the outer frame 1, and the upper portion of the post 15 is 75 formed with a socket 17 to receive the lower end of a pin 18. The pin 18 extends through an opening in the outer frame, and it will be seen that by removing the pin 18 from the post 15 the post may be readily removed from the outer frame 1, thereby permitting 80 disengagement of the swinging inner frame 2 from the outer frame. It will be apparent that by means of this construction the parts 85 may be readily assembled and disassembled without the use of bolts or screws.

Formed in the upper part of the inner frame 2 is a channel 19, a similar channel 20 being formed in the lower portion of the inner frame. As indicated in Fig. 3 the inner ends of the channels are closed, as indicated at 21, while the outer ends are open. By virtue of this construction it is possible to slide a pane of glass into the inner frame 2 with the upper edge portion lying in the channel 19 and the lower edge portion in the channel 20. By swinging the inner 95

frame to a position, such as shown in Fig. 3, the glass pane may be readily removed for replacement or other purposes. It will be seen in Fig. 2 that the forward portion of the inner frame 2 engages the inturned flange 8 on the outer frame 1, and it will also be seen that the rear portion of the inner frame 2 is formed with a vertical flange or panel 23, which is engageable with the adjacent portion of the outer frame 1 when the frames are in compacted relation. In this manner it will be understood that two portions of the inner frame engage the outer frame, thereby providing what I term a "two point contact" providing an efficient and effective connection, an extremely simple construction of outstanding practicability for production purposes.

In order to prevent steaming or sweating of the inside of the glass pane or window 22, openings 24 are formed in the inner frame 2 in close proximity to the window and enable air from the outside to pass through the port or opening 11 into a chamber 25 surrounding the inner frame 2, and through the ports 24 to maintain the inside of the window at a substantially lower temperature than otherwise would be created intending to equalize the temperatures on opposite sides of the window. The size of the ports 24 is so chosen as to prevent the egress of too much air, but sufficient for the purpose above described.

When the parts are in assembled or compacted relation, the sash resembles the ordinary sash at present in use. When it is desired to clean the outside of the window, a catch 26 of any suitable construction for holding the parts detachably together, is released and the inner frame 2 swung outwardly about its vertical pivot post 15. By this means the inside of the window 22 may be readily cleaned without the necessity of a person assuming a dangerous or precarious position. While in outwardly swung position the window may be readily and conveniently removed from the inner frame 2. When the parts are in compacted position, any water on the inside of the frames may 50 pass to the outside through the drain ducts 9 and port 11.

As above noted, I have provided a two point contact inner frame as well as a drain, and wish it distinctly understood that, so far as I am aware, I am the first to provide such construction. Other features heretofore enumerated have been found of exceptional value in a device of this character, and while the construction shown and described, admirably fulfills the objects primarily enumerated, it is understood that numerous changes in details of construction and arrangement may be effected without departing from the spirit of the invention, especially as defined in the appended claims.

What I claim as new and desire to secure by Letters Patent is:

1. A window sash comprising an outer frame having vertical and horizontal bars providing an opening, an inner frame within said opening, a pair of horizontally disposed channels in vertically spaced relation on said inner frame, a glass plate with its upper and lower edge portions in said channels thereby permitting convenient removal thereof in a lateral direction, means for pivotally mounting one side of said inner frame to the outer frame for swinging movements about a vertical pivot, and means detachably securing said frames together. 70 75 80

2. A window sash comprising an outer frame of substantial depth and providing an opening, said outer frame having a drain in the base thereof leading to the outside, an inner frame within said opening, and means for mounting said inner frame for vertical swinging movements. 85

3. A window sash comprising an outer frame having an inwardly extending flange at one side providing an opening, an inner frame inside the outer frame and engaging said flange, means for mounting said inner frame for vertical swinging movements, and said outer frame having a drain beneath said inner frame leading to the outside. 90 95

4. A window sash comprising a pair of interfitting frames, means for mounting the inner frame for swinging movements about a fixed pivot, and the outer frame having a drain beneath the inner frame leading to the outside. 100

5. A window sash comprising a window-glass carrying frame having vertically spaced horizontally disposed channels to receive a window-glass, said frame having means for preventing steaming or sweating of one side of the window. 105

6. A window sash comprising an outer frame, an inner frame within said outer frame, said outer frame having a drain beneath said inner frame leading to the outside, a window in said inner frame, and an opening in said inner frame on the inside of said window to prevent steaming thereof. 110

7. A window sash comprising an outer frame of shell construction providing an opening, an inner frame within said outer frame and spaced from the sides thereof, a window in said inner frame, said outer frame having a drain in the lower part thereof leading to the outside, and a fixed vertical pivot for said inner frame to permit the latter to swing from the outer frame, said inner frame having an opening in the inside of said window sash frame to prevent steaming thereof. 115 120 125

8. A sash comprising an outer frame, and inner frame within the outer frame having a pane of glass, said inner and outer frames providing an air passage to permit air from 130

the outside passing to the inside of said window.

9. A window sash comprising a pair of interfitting frames, the outer frame having a drain beneath the inner frame leading to the outside.

10. A window sash comprising a frame,

a window glass in said frame, and said frame having means for preventing steaming or sweating of one side of the window.

In testimony whereof I have hereunto affixed my signature.

LEON MANNING.
